BOILER AND FURNACE INSTALLATION

Henry Kreisinger, Piermont, and John E. Bell,
Brooklyn, N. Y., assignors to Combustion
Engineering Corporation, a corporation of New
York

Application December 19, 1923, Serial No. 681,467

18 Claims. (Cl. 122—235)

The present invention relates to boiler and furnace installations, and especially installations of water tube boilers heated by furnaces burning fuel in suspension, such as pulverized or powdered coal, or even oil. The invention is particularly concerned with cooling provisions for obviating slagging and other difficulties in such installations, and with their circulatory connections to the boiler. In general, the invention aims at effective cooling circulation in the water screen or other cooling device employed; at correlating and harmonizing the circulation in the screen or the like with that in the boiler to the best advantage; at securing an improved arrangement of connections providing flexibility to take care of expansion and contraction and preventing "priming"; and at deriving the utmost advantage from the heating of the water in the screen. How these and other objects and advantages can be realized through the invention will appear from the description hereinafter of the best known embodiments.

In the drawings, Fig. 1 shows a vertical section through an installation comprising a water tube boiler of familiar type heated by a subjacent furnace of the type commercially known as the "Lopulco", the section being taken as indicated by the line 1—1 in Fig. 2.

Fig. 2 is a front elevation of the furnace.

Fig. 3 shows a vertical section at right angles to Fig. 1, taken as indicated by the line 3—3 in Fig. 1.

Figs. 4 and 5 show horizontal sections through the furnace, taken as indicated by the lines 4—4 and 5—5 in Fig. 1.

Figs. 6 and 7 are views similar to Figs. 1 and 3, showing additional cooling provisions and somewhat different circulatory connections.

The boiler shown in the drawings is of a familiar type, comprising a transverse steam and water drum 10 connected to upright front and rear headers 11 and 12 themselves interconnected by banks of "fore and aft" water tubes 13 inclined upward toward the rear,—speaking of "front" and "rear" in reference to the regions where the furnace is fired and whence the products of combustion make exit from its main combustion chamber or space 15, respectively. Generally speaking, the water in the boiler descends in the front headers 11, moves rearward and upward through the tubes 13, ascends in the rear headers 12, and returns forward to the drum 10 through the substantially horizontal watertubes 16 connecting the rear headers 12 to the drum 16,—where the steam generated disengages and

separates from the unvaporized water. The watertubes 13 overlie an opening in the top or roof 17 of the combustion chamber 15, and the furnace gases take a circuitous course through them (as partly defined by the baffling 18) on their way to the stack 19.

The combustion chamber 15 is a large, deep, unobstructed chamber enclosed by walls that slope outward slightly, so that the chamber as a whole expands upward. Powdered fuel with somewhat more than carrying air (say 40% of the total air actually required for proper combustion) is admitted through one or more downward directed burners 20 (comprising an inner fuel pipe or nozzle with circumjacent air intakes) mounted in the roof 17 adjacent the front wall 21, and is continually ignited by the heat of the latter and of the furnace. The burning air and fuel stream descends in the front of the chamber 15 until its momentum is overcome by the draft, and then bends upward and ascends in the rear of the chamber, whence the products of combustion make their exit to the superjacent boiler. Additional air for combustion is admitted, as required, through damper controlled and regulated intakes 22 opening through the front wall 21 at various heights. The combustion chamber 15 is so deep as to permit substantially complete combustion therein before the products of combustion pass to the boiler.

The air admitted at the front wall inlets may preferably be preheated. For this purpose, the combustion chamber wall may be built hollow, with a narrow space between the very highly refractory lining 23 and the outer shell 24, and the air may be passed through this interspace on its way to the inlets 22,—thus also cooling the walls somewhat. The intramural space is divided into horizontal ducts 25 at the levels of various inlets 22, so that the distribution of the air over the lining 23 can be controlled and regulated by controlling the flow of air through the ducts. Opposite the intakes 22 in the lining 23 are damper-controlled and regulated air intakes 26 in the outer shell 24, by means of which outside air can be admitted directly through the openings 22, either in lieu of the heated air, or in admixture with it,—to regulate its temperature and assure adequate cooling in the zone 25. The rear combustion chamber wall 27 is shown solid, with a correspondingly thicker inner lining 23 of very highly refractory material.

The relatively heavy incombustible residue from the fuel falls or precipitates toward the floor 28 and toward the walls of the chamber 15, in a

finely divided and molten condition. The refuse particles falling directly to the floor encounter and pass through a cooling zone in the lower region 30, and are thus cooled below fusion or slagging temperature. Hence they do not run together or aggregate into a solid mass on the chamber floor 28,—that could only be removed with difficulty,—but simply collect as dust that can be easily sucked out or otherwise removed. 10 Such cooling zone 30 may be maintained either by an excess of air admitted through some of the lower openings 22, or by a "water screen" consisting of a bank of watertubes 31 (sloping upward toward the rear) at a suitable height above the floor 28,—or by both. The screen 31 also absorbs radiant heat from the refuse deposit on the floor 28, and prevents refusion thereof by such heat from the region of combustion above the screen. The particles passing from the flames 15 to the rear chamber wall 27 come under the cooling influence of watertubes 32 ranged upright substantially thereagainst at suitable intervals. Such particles either bounce off and so fall to the floor 28, or, if they adhere, do not form a hard 20 coating with fused runny inner surface, but a loose, friable mossy or whisky deposit, very easily removed. Hence there are no runny masses of hard slag clinging tenaciously to the wall just above the cooling zone 30; and, a fortiori, 25 no superficial fusion and wastage or erosion of the refractory wall itself.

As here shown, the screen tubes 31 are connected between the front and rear waterspaces of the boiler, in parallel with the main boiler tubes 13, and the rear wall tubes 32 are similarly connected. At the front, the ends of the screen tubes 31 are secured in one or more headers 33 which are connected to the front drum 10 by downtake pipes 34; at the rear, the tubes 31 30 are secured in one or more headers 35 into which are also secured the lower ends of the upright wall tubes 32, and the latter are bent outward through the wall 27 at their upper ends and secured in one or more headers 36 that are connected by uptake pipes 37 and double-faced headers 38 and tubes 16^a to the steam space of the boiler. Thus the screen tubes 31 and the wall tubes 32 are connected in series; the former form part of the downtake connections for the latter, 35 and the latter part of the uptake connections for the former. The circulatory connections formed by the downtake and uptake pipes 34 and 37 are in duplicate at opposite sides of the furnace.

The connection of the upcomer pipes 37 into the boxes 38 in turn connected into a group of tubes is very advantageous in that the connection is not only flexible—thus taking care of expansion and contraction—but also priming is prevented because the mixture of water and steam coming up from the screen is distributed and delivered into the drum in a horizontal direction.

As shown, in Fig. 2, there are a number of the powdered fuel burners 20, divided between the right and left sides or halves of the combustion chamber 15, and, of course, individually operable and regulable in the usual manner. As shown in Figs. 2, 3, 4, and 5, the tubes 31 and 32 and their various circulatory connections described above are similarly divided. Specifically, there are separate headers 33, 35, 36, and 38 for the tubes 31 and 32 at opposite sides of the furnace; and the circulation pipes 34 and 37 are connected to the outer ends of the corresponding headers. At the front (Fig. 2), the outer ends

of the headers 33 are supported by the pipes 34, while their inner ends rest on roller supports 39 mounted on the front wall 21. Not only, therefore, is it impossible for stoppage in the connections for either half of the tubes 31 and 32 to affect the rest; but it is possible to shut down the burners 20 at one side of the furnace completely and still have substantially as powerful circulation through the tubes 31 and 32 for the active half as if the idle half were being operated at the same rate as the active one.

While considerable variation is admissible or required under the varying conditions of different installations, in that illustrated 3" to 4" tubes spaced about 14" on centers represents fair practice for the tubes 31 and 32.

Figs. 6 and 7 illustrate an installation in which there are not only screen tubes 31 and rear wall tubes 32, but also tubes 42 ranged upright substantially against the side walls of the combustion chamber 15, to obviate any hard coating or other slag formation difficult to remove on the sides of the chamber,—which might otherwise occur to some extent if the furnace were forced. These side wall tubes 42 may have the same size and spacing as the tubes 31 and 32. They are connected between the front and rear waterspaces of the boiler, in parallel with the main boiler tubes 13 and with the serially connected tubes 31 and 32.

In the installation of Figs. 6 and 7, the circulatory connections for the tubes 31 and 32 are modified somewhat as compared with Figs. 1-5: the downtake pipes 34 to the headers 33 are connected to the lower ends of the front boiler 110 headers 11, and the uptake pipes 37 from the headers 36 to boxes 38 connected to the lower ends of the rear boiler headers 12,—so that the circulation through the tubes 31 and 32 acts to reinforce that through the lowermost tubes 13. The lower and upper ends of the side tubes 42 curve out through the side walls of the furnace, and their connections resemble those of the tubes 31 and 32 in Figs. 1-5. That is to say, the lower and upper ends of these tubes 42 are secured, 115 respectively, to lower headers 43 themselves connected to the front boiler drum 10 by downtake pipes 44, and to upper headers 46 which are connected to the rear portions of the return tubes 16^a by uptake pipes 47 and double-faced headers 48. As shown in Fig. 6, the lower and upper side headers 43 and 46 slope upward toward the rear like the tubes 31, to improve the flow through them. The downtake and uptake pipes 44 and 47 are connected to the front lower and rear upper 120 ends of the headers 43 and 46. The side tubes 42 and their circulatory connections are divided and independent as between the two sides of the combustion chamber 15, much as in the case of the tubes 31 and 32.

In Figs. 6 and 7, various parts and features have been marked with the same reference characters as in Figs. 1-5, as a means of dispensing with merely repetitive description.

We claim:

1. The combination of a pulverized fuel furnace with a superjacent watertube boiler; spaced watertubes ranged upright against the furnace combustion chamber wall with their upper ends bent outward therethrough; a down flow connection from the steam and water drum of the boiler to the lower ends of said tubes, a header connected to the upper ends of said tubes, and an upflow connection from said header to said steam and water drum of the boiler, said connections 145

- connecting said upright tubes with the boiler in parallel throughout with the tubes of the boiler.
2. A boiler having a steam and water drum and water tubes connected to said drum and arranged to cause the boiler water to circulate between the drum and the tubes when the tubes are heated, a furnace to supply heated gases to the boiler tubes, horizontally inclined slag-screen tubes extending across the furnace, connections between the lower ends of the slag-screen tubes and the boiler, a horizontal header connected to the higher ends of the slag-screen tubes, a plurality of tubes connected to said horizontal header and extending upwardly, a pair of inclined upper headers each connecting the upper ends of a group of said upwardly extending tubes, and connections between the higher ends of said upper headers and the boiler drum independent of the connections between the water tubes and their connections to the drum.
3. A boiler having a steam and water drum and water tubes connected to said drum and arranged to cause the boiler water to circulate between the drum and the tubes when the tubes are heated, said drum extending across the boiler tubes, a furnace to supply heated gases to the boiler tubes, horizontally inclined slag-screen tubes extending across the furnace, connections between the lower ends of the slag-screen tubes and the boiler, a horizontal header connected to the higher ends of the slag-screen tubes, a plurality of tubes connected to said horizontal header and extending upwardly, a pair of inclined upper headers each connecting the upper ends of a group of said upwardly extending tubes, and connections between the higher ends of each of said upper headers and one end of the boiler drum independent of the connections between the water tubes and their connections to the drum.
4. A boiler having a steam and water drum and water tubes connected to said drum and arranged to cause the boiler water to circulate between the drum and the tubes when the tubes are heated, a furnace to supply heated gases to the boiler tubes, horizontally inclined slag-screen tubes extending across the furnace, connections between the lower ends of the slag-screen tubes and the boiler, a horizontal header connected to the higher ends of the slag-screen tubes, a plurality of tubes connected to said horizontal header and extending upwardly, and connections between the upper ends of said upwardly extending tubes and the boiler drum independent of the water tubes and their connections to the drum, said last-named connections including a vertical riser pipe of relatively large area and a plurality of smaller horizontal pipes connecting the upper end of said vertical riser pipe and the drum.
5. A boiler having a steam and water drum and water tubes connected to said drum and arranged to cause the boiler water to circulate between the drum and the tubes when the tubes are heated, a furnace to supply heated gases to the boiler tubes, horizontally inclined slag-screen tubes extending across the furnace, connections between the lower ends of the slag-screen tubes and the boiler, a horizontal header connected to the higher ends of the slag-screen tubes, a plurality of tubes connected to said horizontal header and extending upwardly, a pair of inclined upper headers, each connecting the upper ends of a group of said upwardly extending tubes, and connections between the higher ends of each of said upper headers and the boiler drum independent of the connections between the water tubes and their connections to the water
- tube and their connections to the drum, said last-named connections including a vertical riser pipe of relatively large area and a plurality of smaller horizontal pipes connecting the upper end of said vertical riser pipe and the drum.
6. A boiler having a steam and water drum and water tubes connected to said drum and arranged to cause the boiler water to circulate between the drum and the tubes when the tubes are heated, a furnace to supply heated gases to the boiler tubes horizontally inclined slag-screen tubes extending across the furnace, connections between the lower ends of the slag-screen tubes and the boiler, a horizontal header connected to the higher ends of the slag-screen tubes, a plurality of tubes connected to said horizontal header and extending upwardly along the inner face of a furnace wall with their upper ends extending through the furnace wall to the exterior thereof, a header connecting the upper ends of said tubes outside the furnace wall, said header being inclined, and connections between the high end of said header and the boiler drum independent of the boiler water tubes and their connections to the drum.
7. A boiler having a steam and water drum and water tubes connected to said drum and arranged to cause the boiler water to circulate between the drum and the tubes when the tubes are heated, a furnace to supply heated gases to the boiler tubes, horizontally inclined slag-screen tubes extending across the furnace, connections between the lower ends of the slag-screen tubes and the boiler, a horizontal header connected to the higher ends of the slag-screen tubes, a plurality of tubes connected to said horizontal header and extending upwardly along the inner face of a furnace wall with their upper ends extending through the furnace wall to the exterior thereof, a pair of inclined headers each connecting the upper ends of a group of said tubes outside the furnace wall and connections between the higher ends of the headers and the boiler drum independent of the boiler water tubes and their connections to the drum.
8. A boiler having a steam and water drum and water tubes connected to said drum and arranged to cause the boiler water to circulate between the drum and the tubes when the tubes are heated, a furnace to supply heated gases to the boiler tubes, tubes extending upwardly along the inside of at least one of the furnace walls having their upper ends bent outwardly and extending through the wall, a pair of inclined headers each connecting the upper ends of a group of said tubes and connections between the higher end of each inclined header and the boiler drum independent of the boiler water tubes and their connections to the boiler drum.
9. The combination with a boiler furnace having an outlet, of means for introducing fuel to be burned in space therein, a boiler subject to the outlet flow, a water screen in the lower part of the furnace for cooling descending refuse particles precipitating therethrough comprising a row of spaced water tubes extending across the furnace, a row of upright spaced tubes extending along a wall of the furnace and connected serially with the said water screen, the tubes of the water screen and the upright row being substantially entirely exposed to radiant heat, a header at the upper end of the upright row into which the tubes thereof are connected, upcomer connections from said header to steam space of the boiler, and downcomer means connecting the

- tubes of the water screen to water space of the boiler, the said upcomer and downcomer connections connecting the water screen and upright rows of tubes with the boiler in parallel throughout with the tubes of the boiler. 5
10. The combination with a furnace and tubular boiler having a steam and water drum, of means for introducing fuel to be burned in space in the furnace, a water screen comprising a row of exposed spaced water tubes extending across the lower portion of said furnace, a downcomer connection from said drum to one end of said row of tubes, and upcomer connections from the other end of said row of tubes to the drum, said connections connecting the water screen with the boiler in parallel throughout with the tubes of the boiler. 10
11. The combination of a furnace with a subjacent water tube boiler; spaced water tubes ranged upright against a furnace combustion chamber wall; a downflow connection from the steam and water drum of the boiler to the lower ends of said tubes; a header connected to the upper ends of said tubes and located outside the furnace; and an upflow connection from said header to said steam and water drum of the boiler, said connections connecting said upright tubes with the boiler in parallel throughout with the tubes of the boiler. 15
12. In combination with a steam boiler having a steam and water drum, spaced vertical headers, and inclined water tubes connecting the headers, a furnace chamber beneath said boiler, spaced water tubes ranged upright against a furnace chamber wall, downcomer means from the steam and water drum of the boiler to the lower ends of said tubes, a header connected to the upper ends of said tubes and disposed at a materially lower level than the water level in said steam and water drum, and upcomer means from said header to said steam and water drum of the boiler, said downcomer and upcomer means connecting said upright tubes with the boiler in parallel throughout with the tubes of the boiler. 20
13. In combination, a furnace having a combustion chamber with one of the walls thereof comprising a system of vertically extending water tubes, a boiler comprising water tubes over which the gases from said chamber pass after leaving the chamber, a steam and water separator connected to said boiler tubes, an upper chamber connected to the upper part of said furnace wall tube system and disposed at a materially lower level than the water level in said separator, a riser connection extending upwardly from said upper chamber directly to said separator and forming the sole upflow connection from the upper chamber to the separator, a second chamber connected to the lower part of said furnace wall tube system, and a downcomer water connection leading directly from the water space of said separator to said second chamber and forming the sole downflow connection from the separator thereto, said boiler and said system being free of circulating interconnections except through said separator. 25
14. In combination, a boiler comprising a bank of boiler tubes, a steam and water drum, and circulating connections between said bank of boiler tubes and said drum, a combustion chamber located below said boiler having a system of upright water wall tubes, an upper chamber connected to the upper part of said wall tube system and disposed at a materially lower level than the water level in said steam and water drum, 30
- upcomer means connecting said upper chamber directly to said drum, a second chamber connected to the lower part of said wall tube system, and downcomer means leading directly from the water space of said drum to said chamber, whereby said boiler and said system are connected to the steam and water drum in parallel. 80
15. In combination, a boiler comprising a bank of boiler tubes, a steam and water drum, and circulating connections between said bank of boiler tubes and said drum, a combustion chamber located below said boiler having a plurality of systems of upright water wall tubes with upper and lower chambers into which the upper and lower ends respectively of the wall tubes connect, said upper chambers being disposed at a materially lower level than the water level in the said steam and water drum, upcomer means connecting the upper chambers of said systems directly to said drum, and downcomer means leading directly from the water space of said drum to the lower chambers of said systems, whereby said boiler and said systems are connected to the steam and water drum in parallel. 85
16. A steam generating installation, comprising a steam and water drum, a circuit comprising a bank of boiler tubes and circulating connections therebetween and the drum, a combustion chamber located below said bank of boiler tubes, and another circuit comprising a set of upright steam generating tubes exposed to the radiant heat in the combustion chamber, lower and upper chambers into which the lower and upper ends respectively of said upright tubes are connected, said upper chamber being disposed at a materially lower level than the water level of said steam and water drum, and circulating connections between said chambers and said drum; whereby said circuits are connected to the steam and water drum in parallel. 90
17. A steam generating installation, comprising a boiler having a steam and water drum, a bank of boiler tubes, and circulating connections between the boiler tubes and the drum, a combustion chamber located below said bank of boiler tubes, means for introducing fuel into the combustion chamber, to be burned in space therein, a plurality of sets of upright steam generating tubes exposed to the radiant heat of the fuel being burned in the combustion chamber, the tubes of each set being connected at their lower ends into a lower chamber, and at their upper ends into an upper chamber, said upper chambers being disposed at a materially lower level than the water level of said steam and water drum, and circulating connections between said upper and lower chambers and said drum; whereby said boiler and said sets of upright steam generating tubes are connected to the steam and water drum in parallel. 100
18. A steam generating installation, comprising a steam and water drum, a circuit comprising a bank of boiler tubes and circulating connections therebetween and the drum, a combustion chamber located below said bank of boiler tubes, and another circuit comprising spaced steam evaporating tubes at a wall of the furnace, the upper part of said second mentioned circuit being disposed at a materially lower level than the water level of said steam and water drum, and circulating connections between said steam evaporating tubes and said drum; whereby said circuits are connected to the steam and water drum in parallel. 110
